UNITED STATES PATENT OFFICE.

GUSTAF SELANDER, OF CHICAGO, ILLINOIS, ASSIGNOR OF ONE-HALF TO ALBERT L. RADLEIN, OF CHICAGO, ILLINOIS.

TOOL-HOLDER.

1,196,161.

Specification of Letters Patent. Patented Aug. 29, 1916.

Application filed June 10, 1915. Serial No. 33,354.

To all whom it may concern:

Be it known that I, GUSTAF SELANDER, a citizen of the United States of America, and a resident of Chicago, in the county of 5 Cook, State of Illinois, have invented certain new and useful Improvements in Tool-Holders, of which the following is a specification.

This invention relates to that class of tool holders in which the stock of the holder is formed with a holding orifice for the cutter blade and with an extension bar or tang for holding engagement in the tool post of a lathe or like machine. And the present improvement has for its object to provide a strong and substantial structural formation and association of parts wherein the thin and flat adjustable cutter blade generally used in "cutting off" operations on lathes is 10 secured in place in a firm and rigid manner, with an avoidance of any tendency to chatter in actual use, all as will hereinafter more fully appear.

In the accompanying drawings: Figure 1, 15 is a perspective view illustrating the general arrangement of parts. Fig. 1^a, is a perspective view of a boring tool adapted for use in the holder. Fig. 2, is a side elevation. Fig. 3, is a transverse section on line 20 x—x, Fig. 2. Fig. 4, is a similar view of a modified arrangement of parts.

Similar reference numerals indicate like parts in the several views.

Referring to the drawings, 1 designates 25 the main body or stock of the holder, provided with an extension bar or tang 2, by which it is secured in the tool post of the slide rest of a lathe or like machine. In the present improvement the aforesaid bar or 30 tang 2, is offset from the aforesaid main body 1, so as to be in a plane to one side of the hereinafter described elongated cutter blade when the same is in place within the holding orifice in said main body, now to be 35 described.

3 designates a holding orifice extending longitudinally through the stock 1, and having a wedge form in cross-section, one side wall having a vertical disposition and the 40 companion side wall having an inclined disposition as shown.

4 designates a thin flat strip of tool steel constituting the high-speed cutter blade generally employed in metal working opera-

tions, and which blade is adapted to be 55 clamped laterally against the above described vertical side wall of the longitudinal orifice 3 of the stock 1, by means hereinafter described.

5 designates one or more set-screws turning in the top portion of the stock 1, and having bearing upon the top of the cutter blade 4 to prevent any vertical movement or shift of the same.

6 designates a wedge shaped clamping block disposed within the longitudinal holding orifice 3 aforesaid, and having an inclined side corresponding to and in bearing engagement with the inclined side wall of the orifice 3. The opposite side of said 70 clamping block 6 has a vertical disposition and is adapted for bearing engagement with the adjacent vertical side of the cutter blade 4. In the present structure said clamping block 6, is of less height than its holding orifice 3, and is adapted to have limited independent vertical movement therein, in an assemblage or disassemblage of the tool parts.

7 designates a vertically disposed binding screw having the usual operating head or top, and screwing through a screw-threaded orifice in the hub formed therefor on the top portion of the stock 1. Said binding screw has bearing against the top surface of the 85 clamping block 6, aforesaid, midway the length thereof, and is adapted to force said clamping block downwardly in the holding orifice 3, and in such downward movement said block receives a simultaneous and 90 powerful lateral movement to very effectively clamp the cutter blade 4, in place.

8 designates a transverse orifice formed in the stock 1, and intersecting the aforesaid longitudinal holding orifice 3 in a plane beneath the binding screw 7. Said transverse orifice 8, is adapted, in some uses of the present tool holder, to receive a round boring rod 9, shown in Figs. 1^a and 4, and which is clamped in place by the binding screw 7, 100 above described.

In the manufacture of the present holder the holding orifice 3, will usually be formed by the usual drifting method where however it is desired to form the same by a 105 "milling" method, a longitudinal opening will be formed in one of the side walls of the said holding orifice, as illustrated in Fig. 4,

which opening may be left open or closed by a plug brazed therein as found most desirable.

Having thus fully described my said invention what I claim as new and desire to secure by Letters Patent, is:

1. A tool holder, comprising a stock formed with a longitudinal holding orifice, the outer side wall of which is vertical and the inner side wall of which is inclined, an integrally formed holding tang having offset relation to the aforesaid inclined wall of the holding orifice, a wedge block disposed in said holding orifice and adapted to clamp a cutter blade against the outer vertical wall of said orifice, and a binding screw having engagement against the top of said wedge block.

2. A tool holder, comprising a stock formed with a longitudinal holding orifice one side wall of which is vertical and the other side wall of which is inclined, an integrally formed holding tang offset from the stock and in a plane to one side of the holding orifice thereof, a wedge block disposed in said holding orifice and adapted to clamp a cutter blade against the vertical wall of said orifice, a binding screw having bearing on the top of said wedge block, and a plurality of set-screws disposed at opposite sides of the binding screw aforesaid and adapted for engagement with the top of a cutter blade.

Signed at Chicago, Illinois, this 5th day of June, 1915.

GUSTAF SELANDER.

Copies of this patent may be obtained for five cents each, by addressing the "Commissioner of Patents. Washington, D. C."
